UNITED STATES PATENT OFFICE

2,383,939

TOY GUN

Robert W. Marshall, Santa Clara, Calif.

Application April 30, 1943, Serial No. 485,183

6 Claims. (Cl. 46—192)

This invention relates to toy guns, and more especially to a gun which simulates a machine or "tommy" gun, and which can be made entirely of one material, such as wood.

An object of the invention is to provide a simple inexpensive play gun for children, as well as a practice gun for recruits, which, when operated in a simple manner, will produce a realistic rattle or noise similar to shooting off a machine gun or tommy gun, as used by present-day soldiers.

Another object is to provide a noise-making device of the clapper or tic-tac type, in combination with a war-like gun.

A further object is to provide a child's toy which, in these war days of metal scarcity, can be made entirely of another material, such as wood.

All these and other objects, as suggested herebelow, are attained by the method and means now to be described, and illustrated in the accompanying drawing, in which—

Figure 1 is a side elevational view of a preferred embodiment of the invention, in realistic proportions to simulate a present-day tommy gun.

Fig. 2 is a cross-sectional view, taken through plane 2—2 of Fig. 1, showing the details of the noise-making elements, and

Fig. 3 is an enlarged fragmentary side-elevational view, showing the operating handle with its noise-making elements.

Like numerals refer to like parts throughout the several views.

In the embodiment shown, the device comprises a main body-and-handle member 10, shaped as shown, one end being stock-shaped, to fit against the shoulder when in use, and the lower edge near the other end being formed into a series of arc-shaped scallops 10a, the noise-making purpose of which will be hereafter described. This member may be cut from an inch-thick board.

Longitudinally positioned above scallops 10a, and cut into each surface of member 10 is an elongated slot 14, Figs. 1 and 2. Fastened along the upper straight edge of member 10, which has been concaved to receive it, as shown in Fig. 2, is a tubular member or dowel 11, to simulate the gun barrel. Its outer end terminates in another dowel 12, of smaller diameter, concentrically set into its end; and a concentric hole 13 is bored into this outer gun barrel end, to more realistically simulate an actual bored-out gun barrel. The shape of this part of the barrel is shown in inset cross section in Fig. 1.

A trigger 15, and guard wire 16, shown in Fig. 1, may also be made of wood, if desired, and is only for the purpose of effect.

The noise-making handle 17 is shaped to simulate the holding handle of the tommy gun, only in this case it is moved longitudinally to make the noise of shooting the gun. It consists of the inner member 17, with its center portion cut away from the top edge, as shown by dotted outline in Fig. 3, with thinner side members 18, 19 secured thereto and extending beyond the upper edge thereof, substantially as shown. Strips 22, 23 are slidably positioned in groove 14, and the assembled handle brought over them, when the inner upper-edge surfaces of members 18, 19 are secured, as with brads, to said strips 22, 23, as clearly shown in Fig. 2.

Before the handle 17 is thus positioned, however, a flexible strip or noise-making reed or clapper 21, Figs. 2 and 3, has been secured in a slot below the cut-out portion of member 17, and projects upwardly, its upper end being long enough when positioned on the gun stock to engage between the scallops thereof, and, when flexed while being pushed in either direction, to ride over the top of each scallop. And as it is released from each scallop in this way, it springs against the near edge of the next scallop with a clap-like sound, which, multiplied rapidly by movement of the handle along all the scallops, simulates with surprising realism the sound of shooting the tommy gun.

In operation, the child or embryo soldier places the gun against his shoulder in the usual way, sights along the barrel or along simulated sights thereon (not shown), grabs the handle 17 and pushes it back and forth to make the desired noise.

The hollow construction of handle 17, with its 40 diaphragm-like thin sides, forming a chamber for reed 21, intensifies the sound thereof, and its realism. Variations in sound may be effected by making the reed of metal or other material, and altering the acoustical effects of its container, 45 and the co-acting scallops. Other variations to the main invention will readily suggest themselves.

Having now described the invention, what is claimed as new and for which Letters Patent of the United States are desired is:

1. A toy gun comprising a gun stock, a barrel attached thereto, and a handle adapted to be moved under the barrel and to and from the stock, said handle including means for making a noise when so moved.

2. The invention as in claim 1, there being a plurality of downwardly-extending scallops on the lower edge of the gun stock, and a flexible reed in the handle and adapted to engage said scallops successively during said movement to produce a noise.

3. The invention as in claim 1, said handle being hollow with surrounding acoustical surfaces and containing a flexible reed, and means on the gun stock for engaging and moving said reed to make a succession of sounds.

4. A noise-making device, including a hollow handle, a flexible reed therein, and a handle-mounting member adapted to slidably hold the handle, said member including means co-acting with said reed for providing a series of sounds when relative movement is imparted to the handle and member.

5. A toy tommy gun, comprising a gun stock, a barrel secured thereto, a slot in the stock, and a handle adapted to slide therein, the handle having a sounding reed-like member surrounded by noise-conducting walls of the handle, and a serrated surface on the gun stock, each serration being adapted to momentarily engage the near end of the reed when the handle is moved.

6. In a noise-making toy, two parts slidably engaged with each other in order that one part may be reciprocated with respect to the other, and cooperative means on said parts operable to produce a staccato sound effect upon the reciprocation as aforesaid.

ROBERT W. MARSHALL.
